PLUMBER'S LADLE

Joseph Rigano, Larchmont, N. Y.

Application February 24, 1947, Serial No. 730,382

2 Claims. (Cl. 22—86)

1

This invention relates to a plumber's ladle for caulking pipe joints with hot lead.

Frequently such pipe joints, particularly in the case of soil pipe joints are located so close to ceilings as to preclude the use of ladles now available and it is common practice in such cases to cut through the ceilings and floors and pour the lead from above the ceilings, which is wasteful of time and damaging to the ceilings and floors.

To overcome these difficulties I have provided a plumber's ladle which may be used conveniently in such difficult locations, which is easy and natural to use, since the lead contents may be discharged by the simple tilting of the ladle to which plumbers are accustomed, and hence requires no unusual operation in its use.

I accomplish these objects by a plumber's ladle comprising a large, relatively wide, shallow ladle with low vertical walls which converge at the spout end of the ladle, the cavity of the ladle having a relatively deep portion, the bottom of which lies in a horizontal plane, and an inclined portion, the bottom of which lies in a plane slightly inclined upwardly with respect to the bottom of the deep portion, and having a spout which consists of a narrow vertical slit at the convergence of the walls, extending to the inclined bottom, the ladle having a convenient handle and lift.

It is a further object of my invention to provide such a ladle of durable construction which can be inexpensively manufactured.

Referring to the drawings, which show one embodiment of my invention in which

Fig. 1 is a plan view of the ladle;

Fig. 2 is a section on line 2—2 of Fig. 1;

Fig. 3 is a diagrammatic side elevation showing the effect of varying lengths of the deep and inclined portions of the ladle.

As shown in the drawings, 1 designates the ladle proper; 2 the relatively deep portion; 3 the inclined portion; 4 the horizontal bottom of the deep portion 2; 5 the bottom of the inclined portion 3; 6 the rear wall and 7 the side walls of the deep portion 2; 8 the converging side walls of the inclined portion 3. The line 9 indicates the line of demarcation between the bottom portions 4 and 5 which are integral, 10 the longitudinal axis of the ladle, and 11 the intersection of the longitudinal axis 10 with the cross-axis or line 9.

2

The side handle 12 is welded or otherwise secured to side wall 7 in the vicinity of the junction of the deep and inclined portions 2 and 3, and 14 is the rear end lift likewise secured to the rear wall 6 in the vertical plane of axis 10.

Walls 6, 7 and 8 are low and respectively form right angles with their adjacent bottom portions 4 and 5 each of which is flat. 16 is the vertical slit which separates side walls 8, the slit extending for the full depth of the side walls, 17 is the lower extremity of the slit and may be rounded to facilitate the passage of the lead over it.

The inclination of the bottom portion 5 to the horizontal bottom portion 4 is such that the lower extremity 17 of slit 16 should not be higher than the top of rear wall 6, when the bottom portion 4 is held in a horizontal plane.

Handle 12 is secured as aforesaid to side wall 7 in the vicinity of the line of division or cross-axis 9 so that tilting the ladle to discharge the lead will substantially be about the cross-axis 9.

The preferable construction is to have horizontal section 2 and inclined section 3 of equal length, measured along the longitudinal axis 10, and as short as possible, providing the capacity by increasing the width of the deep portion 2, the walls 6, 7 and 8 always being low.

Fig. 3 diagrammatically illustrates the saving in clearance required above the pipe joint by observing these principles. Fundamentally what is desired is a ladle of convenient size, which can be accommodated between the joint and the ceiling and will not require more room than its own overall height to be tilted to completely discharge its contents.

In Fig. 3, 18 indicates a pipe joint to be caulked in pipe line 19, and 20 the ceiling above the pipe line, illustrating diagrammatically ladles of the type heretofore described with the inclined portions 3 and horizontal portions 2 respectively of equal and unequal length, 9 showing the line of demarcation between the two sections. 21 indicates such a ladle with the horizontal portion terminating at that point and of equal length to the inclined portion 2, while 22 indicates a longer horizontal portion 2. Considering a ladle with horizontal and inclined portions of equal length, it will be seen that with its horizontal portion 2 parallel to pipe 19, the ladle easily fits in the space between pipe 19 and ceiling 20, as shown by the

full lines, and when tilted so that the inclined portion 3 becomes parallel to pipe line 19, as shown by the broken lines, in which position the contents of the ladle will be completely discharged, the ceiling 20 easily clears the rear end 21 of the horizontal or deep portion 2 so that such a ladle requires no greater height of space above the joint 19 than its own overall height, to be tilted and to discharge its lead. On the other hand, if the length of the horizontal portion is increased, say to 22, then when the inclined portion 3 is tilted so as to be parallel to pipe line 19, the rise of rear end 22 is much greater and extends above the ceiling. I have found, however, that it is practicable to advance the line of division 9 towards the spout end 17 to the extent that the length of the horizontal section 2 is about 60% of the overall length of the ladle cavity along the axis 10.

Preferably the ladle 1 is cast of iron in one piece and the inner surfaces of bottom portions 4 and 5, and walls 6, 7 and 8 may be ground to a smooth finish. It may also be made of a single piece of sheet metal of about $3/16$ inch thickness flanged to provide the walls 6, 7 and 8 suitable notches being cut at the respective junctions of said walls to provide a proper fit and then welding the joints. Side handle 12 may be made of a strip of sheet metal flanged at 12a and likewise lift 14.

The dimensions of the ladle will vary according to the capacity desired for the size of joints to be caulked.

I have found that a ladle having the following approximate dimensions will provide a capacity of $3\frac{1}{2}$ pounds of lead, suitable for caulking a 3 to 4 inch joint, and is convenient and practical, it being understood that variations in these dimensions are possible without losing the advantages of my invention: Combined inside length of the deep portion 2 and inclined portion 3, 12 inches; inside width along cross-axis 9, 7 inches; inside length of bottom portion 4, 7 inches; inside length of inclined bottom portion 5, 5 inches; inside height of walls 6, 7 and 8, $\frac{3}{4}$ inch; width of slit 16, $3/16$ inch; length of side handle 12, 6 inches and of rear lift 14, $1\frac{1}{2}$ inches.

The use of the ladle is obvious from the foregoing description. The ladle is filled, so that when held with bottom portion 4 in a horizontal plane, the level of the lead will be below the extremity 17 of spout 16. Handle 12 is grasped in one hand and the other hand lifts rear lift 14, thus tilting the ladle substantially about the cross-axis 9. When the inclined bottom portion 5 reaches the horizontal plane the contents will be discharged through the spout 16. It is well known that sufficient lead should be carried by the ladle to enable the joint to be completely caulked in one operation, since repeated partial caulks with fresh charges of lead leave imperfect joints.

In referring to measuring the lengths of the relatively deep and inclined portions of the ladle along the axis 10, my intent is to indicate the direction of measurement, which will follow the

horizontal and inclined bottom portions and not to foreshorten such measurement of the inclined portion by any projection of such axis 10 upon it.

It is obvious that changes may be made in the embodiment of my invention hereinabove described without departing from the spirit of the invention as defined in the appended claims.

I claim:

1. A device for use in caulking pipe joints with liquid metal comprising a ladle having a bottom one portion of which lies in a horizontal plane and the remaining adjacent portion in a plane inclined upwardly from said horizontal portion, said inclined portion tapering to a blunt-pointed end away from said horizontal portion, a vertical wall enclosing said bottom having at the pointed end of said inclined bottom portion a narrow, vertical opening extending for the full height of the wall constituting the spout, the bottom of said opening not being higher than the top of said wall at the opposite end of the ladle, a handle secured to the ladle at said opposite end, and a second handle secured to a side of the ladle substantially at the line of junction of said horizontal and inclined bottom portions, the length of said horizontal bottom portion not substantially exceeding 60 per cent of the combined lengths of both said horizontal and inclined bottom portions.
2. A device for use in caulking pipe joints with liquid metal comprising a ladle having a bottom one portion of which lies in a horizontal plane and the remaining adjacent portion in a plane inclined upwardly from said horizontal portion, said inclined portion tapering to a blunt-pointed end away from said horizontal portion, a wall enclosing said bottom and perpendicular to the respective adjacent portions of said bottom having at the pointed end of said inclined bottom portion a narrow, vertical opening extending for the full height of the wall constituting the spout, the bottom of said opening not being higher than the top of said wall at the opposite end, a handle secured to the ladle at said opposite end and a second handle secured to a side of the ladle substantially at the line of junction of said horizontal and inclined bottom portions, the length of said horizontal bottom portion not substantially exceeding 60 per cent of the combined lengths of both said horizontal and inclined bottom portions, and the width of said horizontal bottom portion being substantially equal to its inside length.

JOSEPH RIGANO.
